Harold V. Jensen, 911 Trenton St.,
High Point, N.C. 27260

Filed June 15, 1966, Ser. No. 2,690

Term of patent 14 years

(Cl. D2—334)

FIG. 1 is a side elevational view of a sock showing my new design as it appears with the cuff portion turned up;

FIG. 2 is a side elevational view of the side opposite thereto;

FIG. 3 is a side elevational view of the side shown in FIG. 1 as it appears with the cuff portion turned down upon itself; and

FIG. 4 is a side elevational view of the side opposite thereto.

The foot form shown above the sock in FIGS. 3 and 4 is for the purposes of illustration only.

I claim:

The ornamental design for a sock, as shown and described.
